UNITED STATES PATENT OFFICE.

GEORGE W. MILLER, OF WOONSOCKET, RHODE ISLAND.

MACHINE FOR PRESSING AND FINISHING TEXTILE FABRICS.

SPECIFICATION forming part of Letters Patent No. 257,508, dated May 9, 1882.

Application filed February 23, 1881. (No model.)

To all whom it may concern:

Be it known that I, GEORGE W. MILLER, of Woonsocket, Providence county, Rhode Island, have invented certain Improvements in Rotary Cloth-Presses, of which the following is the specification.

My invention relates to machines for pressing and finishing textile fabrics; and it consists in constructing the same, as fully described hereinafter, so as to subject the fabric to both cold and hot pressure, maintain the pressure of the cold and hot appliances uniform, facilitate the adjustment and improve the construction of the apparatus.

15 In the drawings, Figure 1 is a longitudinal sectional elevation of my improved apparatus; Fig. 2 an end view, and Fig. 3 a side elevation, of the same.

The frame of the machine consists of the side pieces, A A', suitably constructed to support the various parts hereinafter described, consisting mainly of two hollow rolls or cylinders, B B', two hollow beds, C C', and suitable guide-rolls, brush-shafts, and adjusting devices. The roll B rotates in fixed bearings above the bed C, which moves vertically between guides a and rests upon levers D, the loose ends of which are connected by rods b to levers E, each of which has its fulcrum upon the sliding box supporting the bearings of the roller B', the bed C' beneath the roller B' being fixed. Owing to this construction, any downward pressure applied to the outer end of the lever E will force the roller B' down upon its bed, and simultaneously and with an equal pressure will force the bed C upward against its roller B. This downward pressure is exerted and regulated by weights W upon levers F, connected to rods d, each of which is attached to the outer end of one of the levers E. The attachment of the rods d and levers E is preferably by the use of some device whereby the pressure upon the levers E may be instantly released in order to prevent the goods being burned should the rolls or beds be too hot.

45 Various devices—astoggles, cams, &c.—may be employed; but I prefer to use eccentrics G, secured to a shaft, H, passing through slots X at the upper enlarged ends of the rods d and arranged between rollers e at the side of each rod. The shaft is provided with a handle, h,

by which it may be turned so as to carry it upward in the slot, and thereby at once relieve the pressure and permit the cloth to travel between the roll and bed. The rolls are geared together in any suitable manner so as to turn in the same direction. In the drawings, a pinion, 5, on the driving-shaft gears with a cog-wheel, 3, on a shaft, Y, above, which shaft also carries a pinion, 6, which imparts motion to the roll B' by meshing with the cog-wheel 2 on the shaft of said roll.

Motion is imparted to the roll B by means of a second pinion, 4, on the end of the shaft Y opposite to that occupied by the pinion 6, which pinion 4 drives the cog-wheel 1 on the end of the shaft of the roll B'. Either or both rolls may be heated or chilled by means of fluid admitted to and carried from the same, as may also the hollow beds C C', as next described.

The hollow roll B and bed C are cooled by means of pipes P O; also, the hollow roll B' and bed C' are heated by means of hot water or other heating agent circulating from any suitable source through the pipes P' O'. These pipes are adjustably attached to the rollers or beds, as shown in Figs. 1 and 2 of the drawings.

In the ironing of fabrics it is sometimes very desirable to subject the fabric first to planishing and pressure between heated surfaces and then to a polishing action between relatively cold surfaces. In such cases it is very important that the heating and planishing devices shall be separate and independent of each other, so that there can be no convection of heat, yet they must be so close together that the fabric can be subjected to the cold polishing while it yet retains the heat imparted by the planishing-rollers. This I effect by the arrangement shown, where the roll B' and bed C' are heated, while the roll B and bed C are not heated, the two being arranged so far apart that heat will not be transmitted from one to the other, and yet so close together that the fabric immediately after being planished will pass to the polishing-rollers.

I have found that a much better polishing is produced by driving the polishing-roll a little faster than the planishing-roll, which may be effected either by making the polishing-roll the largest in diameter or by gearing, as shown in Fig. 3 of the drawings.

Difficulty has been experienced in this class of machines from the unequal expansion of the hollow bed and the curved facing-plate *i*, which is usually made of a different metal, which therefore buckles during the operation, presents an imperfect surface, impairing the surface of the fabric. This is especially objectionable in finishing paper and other fragile goods which are apt to be torn. I overcome this defect by making the facing-block *i* of cast metal and so securing it to the bed that it can expand freely thereon. As shown, the facing-block has dovetailed grooves adapted to similar ribs upon the surface of the bed. I do not here claim this feature, as it will form the subject of a separate application for Letters Patent.

The fabric of paper or textile may be passed over a stretching-roll, *K*, constructed as shown, which distends it and takes out the folds. It may then pass first beneath the roll *B'*, then beneath the roll *B*, and then opposite the brush *L*, which, it will be seen, may be readily arranged so as to brush either surface. This arrangement I do not here claim. In like manner the fabric may be conducted, before passing to the stretcher, past a steamer or spray-tube, *N*, and opposite a brush, *M*, arranged upon either side.

It will be apparent that three or more sets of rolls and beds may be employed, and that the arrangement or use of the brushes, steamer, or stretcher will depend upon the character of the fabric operated upon.

It will also be apparent that a different arrangement of levers or devices may be em-

ployed for simultaneously adjusting the roller *B'* and bed *C*, and that adjustable springs may be substituted for the weights *W*.

Without therefore limiting myself to the precise device shown, I claim—

1. The combination of the roll *B*, having journals turning in fixed bearings, the roll *B'*, with journals turning in sliding boxes, the movable bed *C* and fixed bed *C'*, levers *D*, bearing on the bed *C*, levers *E*, bearing on the sliding boxes of the roll *B'* and connected to the levers *D*, and appliances for depressing and elevating the outer ends of the levers *E*, substantially as set forth. 50

2. The combination, in a pressing-machine, of levers *E*, weighted levers *F*, rods *d*, connecting the levers *E* and *F*, appliances whereby the connection between the levers *E* and rods may by one movement be loosened without disconnecting them, and by another movement may be tightened to bring the weight of the levers *F* upon the levers *E*, substantially as set forth. 55

3. The combination of the levers *E* and *F*, slotted rods *d*, carrying rollers or bearings *e*, the shaft *H*, extending through both rods, and eccentrics *G*, arranged on the shaft between the rollers *e*, for the purpose set forth. 60

In testimony whereof I have signed my name to this specification in the presence of two subscribing witnesses.

GEORGE W. MILLER:
